UNITED STATES PATENT OFFICE.

WILLIAM S. SHERWOOD, OF MACON, GEORGIA.

WINDOW-PLATFORM.

SPECIFICATION forming part of Letters Patent No. 735,915, dated August 11, 1903.

Application filed April 20, 1903. Serial No. 153,510. (No model.)

To all whom it may concern:

Be it known that I, WILLIAM S. SHERWOOD, a citizen of the United States, residing at Ma-
5 con, in the county of Bibb and State of Geor-
gia, have invented a new and useful Window-
Platform, of which the following is a specifi-
cation.

This invention relates to removable devices
employed for supporting articles outside of
10 windows, more particularly bed-clothing, in-
cluding the mattresses, but which may be
employed for supporting various articles; and
it has for its object to produce a simply-con-
structed and easily-applied device which may
15 be readily projected through the window-
opening and supported from the frame there-
of and which may be readily removed when
not in use; and the invention consists in cer-
tain novel features of construction, as here-
20 inafter shown and described, and specified in
the claims.

In the drawings illustrative of the inven-
tion, in which corresponding parts are de-
25 noted by like designating characters, Figure
1 is a perspective view of the device applied.
Fig. 2 is a plan view, inverted, of the plat-
form detached and folded or collapsed.

The improved device consists of a platform
constructed of a central longitudinal member
30 10 of any desired length and provided at one
end with a hook 11, by which it may be cou-
pled to an eyebolt 12 upon the window-sill
13. Connected in pairs at suitable intervals
35 to the central member 10 are lateral mem-
bers 14 15, the adjacent ends of the lateral
members being "halved" together and over-
lapping, so that one common pivot-bolt 16
connects both lateral members to the central
40 member. As many pairs of the lateral mem-
bers may be employed as required, but gen-
erally two will be sufficient, as shown.

By "halving" the adjacent ends of the
lateral members together shoulders 17 are
45 formed, which serve as stops to limit the out-
ward movement of the members, and by form-
ing these shoulders inclined, as shown in Fig.
2, the action is improved and a positive lock-
joint formed which limits the movement in
50 one direction, as will be obvious.

Connecting the lateral members upon op-
posite sides of the central member are spaced
members 18 19, and any required number may

be employed and spaced any required distance
apart.

The members 18 19 will be united to the 55
members 14 15 by bolts 20 21 similar to the
pivot-bolts 16, so that the spaced members 18
19 and the lateral members 14 15 may be col-
lapsed, as shown in Fig. 2, or extended, as in
Fig. 1.

Connected to the upper part of the window-
frame are guys 22 23, terminating in snap-
hooks 24 25, and leading from the outer ends
of the outermost side members 18 19 are guys
26 27, terminating in rings 28 29, adapted to 65
engage the snap-hooks 24 25, as shown.

The guys 22 23 will preferably be connected
to the lintel 30 or the upper portion of the side
members 31 32 of the frame by eyebolts 33 34,
and the guys 26 27 will likewise be connected 70
to the members 18 19 by eyebolts 35 36, as
shown. The guys may be of any suitable ma-
terial—such as small ropes or cables, chains,
or wire rods of sufficient strength to with-
stand the strains to which they will be sub- 75
jected. By this means it will be obvious that
the platform may be distended and supported
from the window in a horizontal position and
afford a convenient shelf or temporary bal-
cony-like structure upon which any desired 80
articles may be exposed to the atmosphere
for any length of time and the apparatus
quickly removed or collapsed for storage when
not required. The upper sections 22 23 of
85 the stays or guys will remain upon the win-
dow; but all other parts will be removed with
the platform.

The supporting-guys may also be utilized
as lines upon which bed or other clothing may
be suspended, if required.

One of the outer members 14 or 15 will be
provided with an eyebolt 37 to form a sup-
port for a stay-wire or cable 38, connected by
its ends to the eyebolts 35 36 and forming a
transverse stay to support the outer end of 95
the platform and materially strengthen and
support it.

The stay 38 may be formed integral with
the guys 26 27, if preferred.

Connecting the lateral members 14 15 upon 100
opposite sides of the central member 10 are
tie-rods 39 40, of any suitable material, to
strengthen and stiffen the structure.

The whole device is very simple in con-

struction, easily applied and operated, and will be found very convenient and useful for the purposes enumerated, especially in localities where it is not convenient to place 5 bedding and other articles requiring the action of sunshine and air in yards or on lawns or other out-of-door localities.

The parts will generally be of wood, but may be of other material, if preferred.

10 The platform may be of any desired size and proportions.

Having thus described the invention, what I claim is—

15 1. In a device of the class described, a platform consisting of a central member having oppositely-extending lateral members movably connected thereto, and a plurality of side bars connected movably to said lateral members and foldable therewith, substantially as specified.

20 2. In a device of the class described, a platform consisting of a central member adapted for detachable connection to a window, spaced lateral members movably connected to said central member and extending in opposite directions therefrom, a plurality of side bars connected movably to said lateral members and foldable therewith, and connecting means between the free ends of said side bars and 25 the window for supporting said platform therefrom, substantially as specified.

30 3. In a device of the class described, a platform consisting of a central member, spaced lateral members disposed in oppositely-extending pairs overlapping at their adjacent ends and each pair movably connected to 35 said central member by a pivot-pin common to both and a plurality of spaced side members movably connected to said lateral mem-

bers and foldable therewith, substantially as specified.

4. In a device of the class described, a platform consisting of a central member, spaced lateral members disposed in oppositely-extending pairs overlapping at their adjacent 45 ends and each pair movably connected to said central member by a pivot-pin common to both and with stop-shoulders adapted to limit the outward movement, and a plurality of spaced side members movably connected to 50 said lateral members and foldable therewith, substantially as specified.

5. In a device of the class described, a platform consisting of a central member having oppositely-extending lateral members movably connected thereto, a plurality of side bars connected movably to said lateral members and foldable therewith, and stay-rods connecting said lateral members upon opposite sides of said central member, substantially as specified.

6. In a device of the class described, a platform adapted to be collapsed and distended transversely, means for the detachable connection of said platform to a window-sill, 65 guys adapted for connection between the outer end of said platform to the upper part of the window, and a flexible stay connected transversely to the outer ends of the platform members, and extending under the floor 70 thereof.

In testimony that I claim the foregoing as my own I have hereto affixed my signature in the presence of two witnesses.

WM. S. SHERWOOD.
